(57) CLAIM

The ornamental design for a fuel tank for motorcycle, as shown and described.

DESCRIPTION

FIG. 1 is a front elevational view of fuel tank for motorcycle showing our new design;

FIG. 2 is a rear elevational view thereof;

FIG. 3 is a top plan view thereof;

FIG. 4 is a right side elevational view thereof, the left side elevational view being a mirror image of that shown;

FIG. 5 is a section view taken along line 5—5 in FIG. 3;

FIG. 6 is a section view taken along line 6—6 in FIG. 3; and, FIG. 7 is a section view taken along line 7—7 in FIG. 3.

The broken line showing of the environment is for illustrative purposes only and forms no part of the claimed design. The portion encompassed by a solid line is the design sought to be patented.
